METHOD FOR GAS RELIEF AND BLOWING OF DIGESTERS FOR CELLULOSE

Börje Sune Nyquist, Kristinehamn, Sweden, assignor to AB Rosenblads Patentverk, Stockholm, Sweden, a Swedish joint-stock company

Filed May 14, 1957, Ser. No. 659,058

1 Claim. (Cl. 162—52)

The present invention relates to a method for gas relief and for the blowing of digesters for cellulose, particularly sulphate cellulose, which method is characterized in that the relief or a part thereof, is carried out through the blowing conduit leading to the diffuser, and that the blowing is carried out immediately after a relief is carried out in this manner.

The invention also relates to a device for carrying out the said method, which device consists of a pipe conduit which connects the top of the digester, preferably at the gas relief screen, with the blowpipe of the digester after the blowing valve of the digester.

In conventional practice for digesting sulphate pulp the final temperature is usually about 170 centigrades and the pressure is about 7 atmospheres. On interrupting the digestion the pressure is reduced by gas relief from the digester to a pressure of 4-5 atmospheres, whereafter the digester contents are blown into a diffuser.

A plant for cooking and washing sulphate cellulose is shown diagrammatically in the accompanying drawing.

The gas relief is carried out from the top of a digester 1 through a screen which top is connected to a trap 3 by means of a pipe conduit 2 in which trap pulp and black liquor brought along are separated out. From the trap 3 the relief gas passes to a condenser 4 in which the heat of the relief steam is recovered in the form of hot water. At the beginning of the reduction of the pressure the gas is comparatively dry and contains a small quantity of turpentine vapours. These are condensed and usually recovered from the condensate. When the relief has been carried on for some time, the gas becomes nearly free of turpentine vapour, but by this time some pulp and black liquor are easily brought along, particularly if the reduction of pressure is carried out quickly. The pulp and the black liquor which are brought along to the trap often cause inconveniences.

The blowing of the digester is usually carried out through a conduit 5, the blowing conduit, from the bottom of the digester through a central cock 6 to which the blowing conduits of a number of digesters are connected. The blowing continues through a pipe conduit 7, which is connected to the central cock 6, and through a rotatable pipe 8 to a diffuser 9. In the diffuser 9 pulp and liquor are deposited, while the temperature of this mixture is lowered through formation of steam on account of the reduction of pressure occurring. The steam which contains as much heat as corresponds to the heat liberated by the reduction of pressure, is carried through the return portion of the rotatable pipe 8 to a central trap 10, where remainders of liquor and pulp brought along are separated, and from there to a condenser 11 where the heat is collected in the form of hot water.

According to another embodiment the blowing is not carried out to a diffuser 9 but to the central trap 10 where the temperature of the pulp and liquor blown is lowered through formation of steam in the same way as in the diffuser. Thereafter the steam which is carried to the condenser system 11, and the pulp and the liquor are allowed to flow down through a rotatable pipe to the diffuser which is provided with a gas outlet directly to the atmosphere.

At the beginning of the blowing the system is filled with air which is carried to the condenser 11 together with

2

steam. Owing to the great quantity of incondensable gases the condenser 11 does not work satisfactorily. The resistance to flow in the condenser 11 and in the following pipe conduit 12 is therefore considerably greater than after the air has been driven out. Therefore the deposit of pulp and liquor in the diffuser at the beginning, before the air has been driven out, needs to be carried out at a pressure amounting to about 2 atmospheres gauges, that is, corresponding to a temperature in the pulp and the liquor of about 130 centigrade. When the air has been driven out and the condensation has started satisfactorily, the pressure in the diffuser 9 decreases and the pulp deposited at the beginning begins to boil. Due to the great foaming which easily occurs with regard to the alkaline liquor some of the pulp brought along is caused to leave with the steam, with the disadvantages which are caused thereby.

In the mixture of pulp and liquor deposited at the beginning of the blowing some air is always admixed therewith. The effect of this admixing is that the digester contents are not held in the diffuser 9, in spite of the fact that the volume of the latter is considerably greater than that of the pulp and the liquor.

Now it has been found that these disadvantages are eliminated if the whole or at least the latter part of the gas relief is carried out through the blowing conduit 7, the diffuser 9 and the condenser system 11 belonging thereto. This is brought about in a simple manner whereby the relief conduit or the screen belonging thereto in the top of the digester 1, is connected by a new pipe conduit 13 to the blowing conduit 5 of the digester before the central cock 6.

According to the other embodiment, when the blowing is carried out directly to the central trap 10 it must be seen to that the resistance to flowing in the condenser 11 and the diffuser 9 is so measured that all air is driven out of both, if the relief is not conducted through a special conduit through the diffuser 9 and thereafter through the central trap 10 and the condenser 11.

The following advantages are gained through this method: No difficulties will arise with pulp and liquor in the trap 3 and the condenser system 4 for the relief. The relief can be carried out extremely rapidly without inconveniences, pulp and liquor brought along stopping in the diffuser 9. Due to this rapid relief a constant time for pressure reduction can be kept from one digestion to another, the result being a more uniform quality of pulp. By means of this gas relief through the blowing conduit 7, the diffuser 9 and the condenser system 11 belonging thereto all air is driven out of these, and the blowing is greatly facilitated. For example, right from the beginning the blowing valve can be entirely open. Due to the fact that the great resistance to flowing in the condenser 11 and the following pipe conduit 12 is eliminated no boiling will take place in the pulp and liquor already deposited, and thereby the horizontal stratification obtained in the diffuser 9 at a blowing satisfactorily carried out, is not either destroyed. In this manner a better washing of the diffuser in all respects is obtained.

Due to the fact that all air has been driven out before the blowing starts, no air is admixed in the diffuser 9 and thereby the digester contents will obtain greater room therein.

Since not the whole relief, but only the latter part thereof must be conducted through the blowing conduit 7, the diffuser 9 and the condenser system 11, about the same amount of turpentine as before can be extracted. Thus, the yield of by-products is not much smaller.

What I claim is:

In a method for gas relief and subsequent blowing of digesters for cellulose cooking wherein during the blowing operation the digester contents of pulp and liquor is

passed to a diffuser and condenser system so as to collect said contents in the diffuser and to condense flash vapors thereof in the condenser, the step of prior to said blowing operation passing relief gases from the digester through said system of diffuser and condenser to drive out air from said system and replace the same with such relief gases.
